SCHOOL DESK UNIT

Edwin J. Santee, St. Louis, Mo.

Application March 12, 1936, Serial No. 68,455

8 Claims. (Cl. 155—95)

This invention relates to desk units of the type employed in school rooms, and having seat and desk elements mounted at the front and rear respectively of each unit, whereby with a plurality of such units arranged in rows in parallel spaced relation, the seats and desks combine to provide complete desk assemblies.

Some principal objects of the invention are: to provide a rigid foldable and rotatable desk combination having a seat in front and a desk in the rear, for the use of two separate pupils, so that neither will disturb the other in regular school work; to provide a compact foldable desk and seat combination rotatably mounted on a base, such that when the desk and seat are folded and rotated ninety degrees from regular position the intervening aisles will be widened and the floor will be accessible for cleaning, calisthenics, fire drills, and for other purposes; to provide a compact folding desk, which while normally anchored to the floor, can be easily removed to clean the floor, and can be stored in small space; to provide means in a desk assembly as described, for independently adjusting the height of the desk and seat elements; to provide in a desk unit as described, the same including a foldable seat hinged relatively close to the vertical axis of the unit, auxiliary supporting means for the seat when lowered for use; to provide in a desk unit of the kind described, a compact and collapsible receptacle for storing books and other articles and retaining them therein even during the handling, folding or turning of the desk; to provide in a rotatable desk unit as referred to, means operable thru the lowering of the seat, for automatically locking the unit in either of four positions to face front, sides or rear of the room, thus preventing rotation of the desk when the seat is occupied; to provide a desk unit of the kind referred to embodying a pedestal, supporting members rotatably mounted on the pedestal, desk, seat and receptacle elements collapsibly or foldably mounted on the supporting members, means for releasably locking the supporting members and attachments at certain predetermined points of rotation relative to the pedestal, and independent means for separately adjusting the desk and seat elements vertically to meet the requirements of various pupils; to provide a desk unit rotatably mounted on a pedestal and including desk, seat and receptacle elements which may be opened out for use as required and adjusted vertically for such use, or which may be folded or collapsed closely towards the vertical axis of the pedestal for providing

the most possible clearance spaces between said units for any purpose required.

Other objects and advantages of the invention will be fully apparent from a perusal of the following specification, reference being had to the accompanying drawings constituting a part thereof, and wherein:

Figure 1 is a side elevation of my desk unit showing in full lines the seat and desk boards in opened positions ready for use and, in broken lines, these parts in their folded positions.

Figure 2 is a frontal elevation of the structure shown in Figure 1.

Figure 3 is an enlarged fragmentary vertical cross section thru the lower portion of the desk unit, taken along the line 3—3 in Figure 2.

Figure 4 is a rear elevation of the upper portion or superstructure of the desk unit, the pedestal and mounting sleeve being omitted.

Figure 5 is a plan view of the pedestal and base alone.

Figure 6 is a perspective view of the mounting sleeve alone.

Figure 7 is a fragmental, enlarged, vertical cross section thru the pedestal and mounting sleeve, showing a modified form of lock for the sleeve.

Figure 8 is a fragmental frontal elevation of the mounting sleeve as equipped for the lock structure shown in Figure 7.

Figure 9 is a side elevation of the upper portion of a desk unit showing a modified form of desk board mounting.

Figure 10 is a plan view of the structure shown in Figure 9.

Figure 11 is an enlarged vertical cross section through a lateral portion of the desk board and showing the upper portion of one of the guide channels, the view being taken along the line 11—11 in Figure 10.

Figure 12 is a fragmental perspective view of one corner of the desk board showing the stop lug extended therefrom.

Figure 13 is a side elevation of the upper end of one of the guide channels, showing the mountings for one of the adjustment slides.

Figure 14 is an enlarged fragmental vertical cross section through the upper portion of the seat structure taken along the line 14—14 in Figure 4 and showing the elongated recess in the top board through which pencils may drop as the seat board is folded.

Figure 15 is an enlarged perspective view of one of the adjustment slides used in connection

with the desk board mounting shown in Figures 9 and 10.

Figure 16 is a fragmental, vertical cross section through the frontal sides of the pedestal and 5 mounting sleeve illustrating still another embodiment of the lock for the sleeve.

In carrying out this invention I provide a hollow mounting pedestal or post 1, wholly or 10 partially tapered, and resembling generally a frustum of a cone, the same being open at its upper end but closed at its lower end as shown at 2, and there being a bolt hole 3 pierced thru this closed end. This pedestal is preferably 15 formed with a flared and elliptical base 4 formed with an annular shoulder 5 immediately adjacent the pedestal. The pedestal and base are locked rigidly to the floor 6 by means of a floor plate 7 sunk in the floor and secured by screws 8. The floor plate is formed with a tapped bore 20 9 for engaging a threaded bolt 10 which is passed down thru the bolt hole 3 of the closed lower end of the pedestal and into the said floor plate.

Four lock slots 11 are cut vertically down thru the upper margin of the pedestal and spaced 25 angularly apart ninety degrees therearound, and four shallow recesses, sockets or pockets 12 with gradient ends 13 are formed in the annular shoulders 5 and spaced also ninety degrees apart.

A complementary mounting sleeve 14 is freely 30 and rotatably seated over the pedestal 1, the body portion thereof also resembling the frustum of a cone similar to the pedestal and being just enough larger than the pedestal to snugly yet freely seat thereover and to frictionally lock 35 thereto when lowered thereupon, owing to the tapered fit or conical seating faces of these elements. The lower annular margin of this sleeve is formed with lock cams, seating lugs or projections 15 with gradient ends 16, these lugs or 40 cams being spaced and adapted nicely to fit or seat into the recesses or sockets 12 of the shoulder 5. The pedestal 1 and sleeve 14 are so formed and related that with the sleeve fully lowered upon the pedestal with their meeting faces frictionally interlocked, and the lock-cams 15 seated 45 within the recesses 12, the bottoms of the cams will not quite touch or contact the bottoms of the recesses. By this arrangement though these elements are rigidly interlocked, the meeting 50 gradient ends 13 and 16 of sockets and lugs enable a relatively slight torque applied to the sleeve 14, even though weighted with a desk, to slightly raise the sleeve and free it, so that it may easily be rotated ninety degrees to any other 55 desired angular position and realignment of cams and recesses. The rear portion of the sleeve 14 is extended upward as shown at 17 and a guide rib 18 is longitudinally extended from top to bottom at the rear and outer side of the sleeve for a 60 purpose to be explained. On the inner face of the sleeve 14 opposite the rib 18 and immediately above the upper edge of the pedestal 1, as these elements stand assembled, a pair of laterally spaced hinge lugs 19 are formed and extended inwardly from the wall of the sleeve, and diametrically opposite these lugs a lock slot 20 65 is cut vertically down thru the margin of the sleeve and adapted to register with either of the slots 11 of the pedestal upon the rotation of the 70 sleeve thereon.

A latch bar 21 is pivotally pinned at 22 between the lugs 19, and its free end is extended outward and shaped to freely slide down into the slot 20 and either of the slots 11 that may be 75 aligned therewith, as represented at 23, thus lock-

ing the sleeve 14 against rotation upon the pedestal 1 until the said latch bar is again raised.

A T-shaped desk support 25 has its vertical leg 26 grooved out longitudinally along its inner face as shown at 27 to slidably receive the rib 18 of the sleeve, the leg 26 being pierced thru its outer face with a plurality of longitudinally spaced bolt holes 28 thru which bolts 29 may be passed into tapped sockets 30 formed in the rib 18, whereby the entire support 25 and of 5 course the desk to be described as mounted thereon, may be adjusted vertically to meet the requirements of various pupils.

The laterally extended arms 32 of the support 25 are provided at their ends with flattened and 15 vertically extended anchor lugs 33, to which are secured the seat and desk supporting brackets 34 by means of bolts 35 passed thru the lugs 33 and the said brackets. The brackets 34 are U-shaped at their lower portions and include the 20 lower and horizontally extended seat supports 36 and the vertically extended back and desk supports 37, the latter being provided at their lower portions with the inwardly extended seat stop lugs 38. Seat bars 39 are hinged or pivoted 25 at points adjacent their rear ends to the free extremities of the brackets 34 in any conventional manner, as by the ball and socket joints 40, and these supports are provided with rearwardly extended arms 41 arranged to span the 30 U-shaped lower portions of the brackets 34 and impinge the under sides of the stops 38 as the bars 39 are turned downward, thus supporting these seat bars in their normal horizontal position. Owing to the bars 39 being hinged closely 35 adjacent their rear ends, the additional bracing afforded by the arms 41 against the stops 38, is very desirable. At the same time this close hinging enables a correspondingly close vertical folding up of the bars to the vertical axis of the 40 unit that strongly contributes to economy of space and compactness. A seat board 42 is extended across and secured to the seat bars 39 in the usual manner. It will be noted that in the operation of raising the seat 42, the rear 45 margin thereof will turn down into the clearance spaces provided by the U-like formation of the lower portions of the brackets 34. A pair of hinge lugs 45 are secured as shown at 46 medially and in spaced relation to the under side of 50 the seat board, and a lock lever 47 has its upper end pivotally pinned as shown at 48 between these lugs. The lower end of this lever is pierced with a plurality of longitudinally spaced adjustment holes 49, thru any selected one of which a short bolt 50 may be passed and screwed into a tapped socket 51 formed in the outer extended end of the latch bar 21. Thus as the seat 42 is lowered for use the lever 47 pushes the latch bar 21 down into the slot 20 of the sleeve 14 and 55 also into either of the slots 11 that may be aligned therewith, thereby locking the assembly in a fixed position against rotation. As the seat is raised however the elements 47 and 21 are raised and folded rearwardly towards the 60 vertical axis of the pedestal 1, as shown in Figure 1 in dotted lines. In lieu of the described locking device, laterally spaced ears 53 may be extended from the outer frontal face of the sleeve 14, one at either side of the slot 20, and 65 a cam 54 then pivoted thru an inner upper corner between these ears, as shown at 55. The cam 54 is adapted and formed to swing down into the aligned slots 20 and 11. The lower end of the lever 47 is then pivoted by means of a 70 75 80 85 90 95 96 97 98 99 100

bolt 50a to the outer upper corner of this cam, after which the vertical movement of the lever 47 operates the cam for locking or unlocking the sleeve 14, to the same effect as the previously 5 described devices.

A still further sleeve locking means is represented in Figures 7 and 8, where shallow grooves 11a replace the slots 11 and a guide tongue 56 is secured at 57 over the slot 20 and flared upwardly and out from the sleeve 14. In this arrangement the lower free end of the lever 47a is tapered off as shown and reciprocates freely vertically, and as the slot 20 and one of the grooves 11a are moved into alignment and the 10 seat board 42 is lowered, the lower free end of this lever will slide thru the slot 20 into the aligned groove 11a of the pedestal 1, thus effectually locking the elements until the seat is again raised. In the operation of this seat, as same 15 is lowered the arms 41 impinge the stops 38, thereby affording thru the long leverage provided a very stable and durable support and which may be in addition to other or conventional seat supports or stops, one of which is 20 represented at 59 in Figure 3.

A seat back 60 is secured as shown at 61 by screws or other conventional means to the frontal faces of the supports 37. A desk supporting bar or hanger board 62 is extended horizontally between 25 the upper ends of the supports 37 and at the rear thereof, being bolted thereto by the bolts 63 which are screwed into transversely aligned and tapped sockets 64 formed in these supports. A series of 30 these sockets 64 being provided at the upper ends 35 of the supports, a ready means is provided for vertically adjusting the height of the hanger bar 62, as also the desk mounted upon this board and to be later described, so as to meet the requirements of various pupils. A desk box or case, comprising a horizontally extended top board 65, side 35 boards 67 and a horizontal brace or drop board 68, all conventionally fastened together, is secured to and suspended from the hanger bar 62 which subtends the space between top board and drop board, 40 and is dropped down or spaced somewhat below the top edge of the hanger bar. This desk unit is fastened to the hanger bar 62 by means of screws 45 69 passed thru the bar 62 into the upper portions of the desk case. A receptacle 70 rectangular in 50 cross section and preferably made of light sheet metal is fitted freely within the space between the side boards 67 and below the brace or drop board 68, and the lower, outer corners of the side boards 67. By this arrangement the receptacle may be 55 pulled out at its upper portion for use, or may be closed in between the side boards out of the way when not in use. Stops 11a limit the outward movement of the receptacle 70.

If the hanger bar 62 be of wood, then metal 60 supporting straps 72 are screwed as shown at 73 to the ends thereof, and elongated strap metal hangers 74, having short, turned ends 74a, are 65 pivotally pinned to the upper ends of the straps 72 by means of rivets 75 passed thru the free extremities of the short ends and thru the straps 72, the said short ends 74a being turned upward. A rectangular desk board 76 is secured by screws 77 between the long arms of the hangers 74.

Owing to the drop of the desk board 76 below 70 the upper margin of the hanger bar 62, it results that in the process of raising and turning up the rear or free portion of this board, the same is automatically drawn away from the hanger bar 62, owing to the offset hinged connection of the desk board to the hanger bar. For this reason

any pencils, erasers or the like that may be left lying upon the desk board, will as the desk board is elevated, automatically fall down thru the space thus created between desk board and hanger board down upon the top board 65 of the desk 5 case, where they may be readily recovered by the pupils. Or if desired, an elongated recess or cut-out 79 may be formed thru the forward margin of the top board 65, contiguous the hanger bar 62, and the pencils will then fall down thru this 10 recess and come to rest upon the inner drop board 68, as represented in Figure 14. This feature greatly facilitates the work of the janitor and prevents loss of the pencils or the like. Moreover, owing to this same offset manner of pivotally or 15 hingedly mounting the desk board below the top of the hanger bar, the desk-board may be swung up and over forwardly of the back 60 of the seat 20 42, and when this seat is turned up vertically, then over forwardly of the seat itself, as illustrated in dotted lines in Figure 1. Thus the elements of the unit may be folded together in a very compact manner.

It will be seen that in the assembly described I have provided a very compact, convenient and efficient form of rotatable and collapsible or foldable desk unit, well adapted to carry out the purposes contemplated, to-wit: a rotatable and foldable desk unit, having seat, desk and receptacle elements adapted when not in use to be turned 25 30 or folded compactly out of the way towards the vertical axis of the pedestal whereon the unit is carried, and having locking means automatically operated by the lowering of the seat to hold the unit in any selected relative position desired. The 35 elements of the unit are of course to be made of materials best suited for the purpose, as cast metal, sheet metal or wood, and as will readily occur to an experienced workman. With a plurality of these units arranged conventionally in 40 rows and properly spaced apart, they may be turned to either side so as to face blackboards on the side walls, or in that position the seats, desk boards and receptacles may be collapsed out of 45 the way of the janitor in his work of cleaning, or for any other purpose. Moreover these desk units are very conveniently adapted for moving and storage.

In Figures 9 thru 12, is illustrated a modified manner of collapsibly mounting the desk board. 50 Here a pair of channel irons 80, forming guides, are mounted with their channels turned inwardly between the seat back 69 and the hanger bar 62, being positioned inside of and secured to the back supports 37 by means of screws 81. The 55 upper ends of the side webs of these bars are cut away as shown at 82 to provide clearances for the operation of the desk board 76. Elongated adjustment slots 83 and bolt holes 84 are formed thru the upper ends of the medial webs of the 60 channel irons. Adjustment slides 85, slotted as shown at 86 and having the turned extremities 85a, are mounted outwardly over the apertured upper ends of the medial webs of the channel irons. For this mounting the extremities 85a of 65 the slides are slidably inserted thru the slots 83 of the channel irons and bolts 87 are rigidly set in the holes 84 with their threaded ends projecting out thru the slots 86 of the slides and thumb nuts 88 are mounted on these threaded ends. 70 Stop lugs 89 are seated in the lateral edges of the desk board 76, close to the forward margin thereof, and these lugs are formed and arranged to slide within the channels of the irons 80, below the inturned extremities 85a of the slides, these 75

inturned extremities thus acting as stops for the lugs 89 in the operation of the desk board. By merely raising the free rear portion of the board 76 to vertical position, this board may then be freely dropped or slid down in the space between the seat back and hanger bar, entirely out of the way. When pulled up for use and turned down horizontally, the desk board fulcrums upon the top of the desk case and the lugs 89 bear up 10 against the stops or extremities 85a of the slides 85. By adjusting these slides up or down and then turning up the thumb nuts, it is obvious that the slope of the desk board may be increased or reduced, as may be desired.

15. In use, these desk units may as heretofore set out, be turned and will automatically seat themselves in any one of four selected positions as provided for by the recesses or sockets and the cams of the pedestal and supporting sleeve, or 20 may be automatically locked in any such position thru the lowering of the seat, and the seats and desk boards may be separately adjusted in height, or may be unitarily so adjusted to meet requirements of different pupils. Other advantages have 25 also already been pointed out. While I have herein recited and shown certain preferred assemblies and structural features of the invention, it is understood that I may vary any of said features in minor details as may be found desirable, 30 not departing from the spirit of the invention, as defined in the following claims.

I claim:

1. In a rotatable desk unit, a pedestal conformed as a frustum of a cone and having spaced 35 slots formed therearound, a complementally formed sleeve rotatably seated upon the pedestal and adapted by reason of the mutually tapered fit to grip same when lowered thereon, the sleeve having a slot adapted upon rotation of the sleeve 40 to register with either one of the slots of the pedestal, a support extended upwardly from the sleeve, a seat hinged to the support and arranged for turning down horizontally over the pedestal or vertically up thereover, and means carried by 45 the assembly co-operating with the slots of pedestal and sleeve and operable thru the lowering of the seat for automatically locking the sleeve against rotation upon the pedestal, in a selected 50 position of rotation, as determined by the selected pedestal slot and its alignment with the slot of the sleeve, the raising of the seat in turn serving to unlock the elements.
2. In a rotatable desk assembly, a round and tapered post having slots spaced therearound in 55 circumferential alignment, a complemental sleeve rotatably seated over the post and adapted by reason of the tapered fit to grip same when lowered thereon, a support extended upwardly from the sleeve, a seat hinged to the support for lowering 60 or raising over the post, and means carried by the assembly and operable by lowering or raising the seat, for automatically locking or unlocking the sleeve against rotation or freeing it for such rotation.
3. In a rotatable desk assembly, a round and tapered post having slots spaced therearound in circumferential alignment, a complemental round and tapered sleeve rotatably seated upon the post and adapted by reason of the tapered fit 65 to grip same when lowered thereon, a support extended upwardly from the sleeve, a seat hinged to the support and arranged for lowering or raising over the post, means co-operating with the said slots of the post and operable by lowering or

raising the seat, for automatically locking the sleeve against rotation or unlocking it for such rotation.

4. In a desk combination in which the front to rear dimension is reduced by collapsing the desk 5 top and seat in a vertical manner, a pedestal support for the assembly, the same comprising a base member, a conical post mounted on the base member, a complemental conical sleeve rotatably mounted over the post and arranged to frictionally grip same through gravity when fully lowered thereon, means operable through torque applied to the sleeve for raising the sleeve for rotation on the post, and means auxiliary to the friction grip of the sleeve upon the post for releasably locking 10 the sleeve to the post in certain selected positions of rotation, said latter means being operable through the lowering of the seat.

5. In a desk combination, a pedestal removably anchorable to the floor, a sleeve rotatably mounted on the pedestal, the sleeve having an upwardly extended portion at its rear side, and there being a guide rib formed longitudinally on the outer face of the sleeve and extension at the rear side thereof, a T-shaped desk support having its vertical leg grooved out for slidably engaging the guide rib of the sleeve, means for adjustably locking the T-shaped desk support in any adjusted position, a vertically foldable seat supported forwardly on the sleeve, and mechanism operable through lowering the seat for locking the sleeve in either of a series of angular positions relative to the pedestal.

6. In a desk combination, a pedestal removably anchorable to the floor, a sleeve rotatably mounted on the pedestal, the sleeve having an upwardly extended portion, there being a guide rib formed longitudinally on the sleeve and extension, a T-shaped desk support having its vertical leg grooved out for slidably engaging the guide rib of the sleeve, means for anchoring the T-shaped desk support in any of a series of adjusted positions on the sleeve.

7. In a desk combination, a pedestal removably anchorable to the floor, a sleeve rotatably mounted on the pedestal, the sleeve having an upwardly extended portion, there being a guide rib formed longitudinally on the sleeve and extension, a T-shaped desk support having its vertical leg grooved out for slidably engaging the guide rib 50 of the sleeve, means for anchoring the T-shaped desk support in any of a series of adjusted positions on the sleeve, and mechanism for locking the sleeve against rotation in either of a series of angular positions relative to the pedestal.

8. In a desk combination in which the front to rear dimension is reduced by collapsing the desk top and seat in a vertical manner, a pedestal support for the assembly, the same comprising a base member, a conical post mounted on the base member, a complemental conical sleeve rotatably mounted over the post and arranged to frictionally grip the same through gravity when fully lowered thereon, there being an upwardly extended portion at the rear side of the sleeve, a T- 65 shaped desk support having its vertical leg mounted on the sleeve and extended portion, means operable through torque applied to the sleeve by the T-shaped desk support as a lever, for raising the sleeve for rotation on the post, and means auxiliary to the friction grip of the sleeve upon the post for releasably locking the sleeve in certain selected positions of rotation on the post.

EDWIN J. SANTEE.
